COMPUTING MACHINE

Frederick A. Hart, Stamford, Conn., assignor to Remington Typewriter Company, Ilion, N. Y., a corporation of New York

Original application January 21, 1927, Serial No. 162,473. Divided and this application October 1, 1931, Serial No. 566,188

3 Claims. (Cl. 287—52.02)

My invention relates to computing machines. In these machines there are parts of the mechanism that are required to move with a considerable degree of precision and at the same time, especially in computing machines of that class in which the computing mechanism is operated by the keys of a typewriter, it is necessary that the parts move freely so as to offer as little resistance as possible to the operation of the key. The present invention has for its principal object to improve mechanism of this character in respect to precision of movement and readiness, accuracy and permanency of adjustment, together with freedom of movement; and to attain these objects with mechanism that may be easily and cheaply manufactured.

To the above and other ends my invention consists in certain features of construction and combinations and arrangements of parts, all of which will be fully described herein and particularly pointed out in the claims.

This application is a division of my prior application Serial No. 162,473, filed Jan. 21, 1927.

I have shown my invention applied to a Remington combined typewriting and computing machine, the general construction and mode of operation of which are well-known to the art. For the purposes of the present invention the machine may, if desired, be made as described in the patent to Wahl No. 1,270,471, dated June 25, 1918, except as hereinafter pointed out. In other words, for the purpose of description the invention in the form in which it is set forth herein may be regarded as an improvement in the mechanical structure of the machine described in said patent.

In view of what has just been said, the accompanying drawings show only so much of the machine as is necessary to illustrate my improvements.

In said drawings, all of which are more or less fragmentary,

Figure 1 is a front view of the right-hand end portion of the computing mechanism;

Figure 2, a right-hand view in section on the line 2—2 of Figure 1;

Figure 3 is an irregular section approximately on the line 3—3 of Figure 1 and looking downward.

Figures 4, 5 and 6 are details in perspective.

Figures 3—6 are on a larger scale than Figures 1 and 2.

The Remington combined typewriting and computing machine comprises a Remington typewriter having attached thereto computing mechanism of the sort described in the Wahl patent above referred to. The actuator of said com-

puting mechanism comprises a main frame casting 10 secured to the top plate of the typewriter and a number of sheet metal frame plates projecting in front and rear planes from said casting. Four of said plates are shown in the drawings and designated 14, 15, 16, and 17. Plate 14 may be regarded as the right-hand end plate of the vertical actuator and it is secured to the main casting 10 by two screws 26. Plate 15 is the left-hand end plate of the cross actuator, the right-hand end plate of which is not shown, but in the machine it is supported on the extreme right-hand end of the casting 10. The frame plates 15, 16 and 17 are supported directly or indirectly from plate 14 and the right-hand end plate, not shown, the supports consisting of certain cross rods or posts, some of which are shown and numbered 21, 22, 23 and 24. Each of the parts marked 21, 22, and 23 consists of a rod running through all of the plates and having sleeves or bushings strung on it to space the plates apart.

Each of the ten numeral keys of the typewriter has connected thereto a link which at its upper end is pivoted to a so-called "fan", the hub of which is journaled on a cross rod of the vertical actuator. This so-called fan has a part adapted to operate a universal bar which is supported by suitable arms on a universal rock shaft 35, Fig. 2. Each fan operates a corresponding goose-neck cam which actuates an arm 43 secured to and projecting from a differential rock shaft 44, which is journaled in the frame plates. This differential rock shaft 44 carries the usual peculiar hub structure to which is pivoted the usual gear sector or segment which operates the vertical master wheel.

Journaled in the frame plates 15 and 16 is the differential shaft 54 of the cross footer on which the gear sector or segment 55 is mounted. The sector 55 is adapted to mesh for addition with the drive pinion 56 and for subtraction with another drive pinion not shown, the pinion 56 being splined on the shaft 57 of the cross master wheel 58, said shaft journaled in the frame plates 15 and 17, all as heretofore. The two differential shafts are driven in unison by a linkage situated between the plates 14 and 15 and comprising an arm 60 fast on the right-hand end of shaft 44, an arm 61 fast on the left-hand end of shaft 54 and a connecting link 62.

The cross actuator also comprises a universal rock shaft 63 which is caused to move in unison with the shaft 35 by means of another linkage also situated between plates 14 and 15 and com-

prising an arm 64 fast on shaft 35, an arm 65 fast on shaft 63 and a connecting link 66.

All the parts above referred to perform substantially the same functions as heretofore.

5 The differential shaft 54 of the cross actuator has ball bearings, 111, 114 and 112, 113, the pressure on which is regulated by a thrust rod 118 and screw 121 in a manner fully described and claimed in another application.

10 It is also necessary that the motion of the upper shaft 44 be transmitted to the lower shaft 54 with ease and precision, and I have accordingly provided ball bearings and certain adjustments which will now be described in the linkage by 15 which these two shafts are connected.

The link 62 is at the right-hand side of the arm 61 and it has a ball bearing groove turned in the body of the link itself and facing toward the right to accommodate balls 122. The cone 20 123 consists of a properly shaped head and bearing part and a stem screw threaded through the arm 61 so as to be adjustable, the adjustment being secured by a set screw at 124 as shown in Figs. 1 and 4, said set screw threaded through 25 the arm 61 and bearing at its end against the screw-threads of part 123. The part of said screw just to the left of the head of the screw is properly turned to constitute a bearing to cooperate with the bearing groove in the link 62. Said link is 30 held properly pressed toward the right to cause the desired engagement with the balls 122 by means of another set of balls 125 which run against the flat left-hand face of the link 62. These balls run in a suitable groove in a ring 35 126, said groove facing toward the right as shown in Fig. 3. The left-hand face of the ring bears against the flat right-hand face of the arm 61. The pull lengthwise of the link 62 is taken entirely by the balls 122, the balls 125 having for 40 their sole function to hold the members of the bearing 62, 122, 123 in proper contact. This form of bearing is of such a sort that it can be adjusted to work smoothly and without lost motion without the necessity of the link 62 being 45 made with great precision in a plane perpendicular to the axis of the cone 123. If the link were not exactly so perpendicular it might happen that only a few of the balls 125 would touch the link 62 at one time but there would always be enough 50 to hold the balls 122 in proper engagement so as not to allow lost motion in the bearing longitudinally of the link.

The bearing at the upper end of the link 62 is in all respects like that just described at the 55 lower end. It includes a cone 127 like the cone 123, a ring 128 like the ring 126 and a set screw 130 like the set screw 124. For convenience of manufacture it is advantageous to have the parts of these two bearings interchangeable.

60 The arm 60 is shown made with a split hub constructed to fit snugly on the end of the shaft 44 where it can be readily adjusted and clamped with great security in adjusted position by means of a clamp screw 131. For the convenience of the assemblers of the machine a shallow slot 132 is cut across the end of the shaft 44 like a screw-driver slot and this slot bears such a relation to the other parts including the segment 47 that in 65 assembling the machine the arm 60 may be so set on the shaft as that the split in said arm registers with this slot 44, thus bringing the arm 70 60 at the correct angle to the segment 47. In order that the motion be transmitted accurately 75 it is not essential that this angle be established

with any greater degree of precision than it can be by eye by the means described.

The lower arm 61 is also made of split hub construction and is provided with a clamping screw 133. In adjusting the machine the gear sector 80 on this shaft may be set by a gage to its normal position and the arm 60 may be secured in its proper position as determined by the slot 132. With the clamp screw 133 loose enough to permit of adjustment, the segment 55 may then be set to its normal position whereupon the screw 133 may be tightened, thus bringing all of the parts 85 into their proper relative normal positions and relations.

Having thus set the two shafts 44 and 54 in their correct normal relations, it may still be that, in operation they do not swing through exactly the same angles. If now the shaft 44 and segment 47 be swung to the position to which the "9" key would move then, it might be found that the segment 55 had been swung a little short of or a little beyond its "9" position. This would be remedied by adjusting the relative lengths of the arms 60 and 61 and I have provided means for doing this, said means in the present instance 90 being applied to the lower arm 61 which can be slightly lengthened in case the sector 55 is found to swing through too great an angle and slightly shortened if said sector is found to swing through 95 too small an angle. To this end the arm 61 does not directly engage the shaft 54 but is mounted on it through the intermediary of a sleeve 134, as 100 shown in Figs. 2 and 6. This sleeve is split throughout its length as shown at 135 and a notch 136 is cut diagonally opposite said slit in the end of the sleeve to accommodate a screw-driver by which the sleeve can be turned. The end of the shaft 54 is reduced and the hole in the sleeve 134 through which this reduced end passes is 105 eccentric to the external surface of the sleeve. If it is necessary to change the length of the arm 61 this can be done by turning this sleeve with a screw-driver, the change in length being brought about by the eccentricity of the sleeve. 110 When the proper adjustment has been reached a tightening of the screw 133 will bind the sleeve 134 against the reduced end of the shaft 54 and will also bind the arm 61 to said sleeve so that 115 the whole thing will work as a rigid arm projecting from the shaft. Adjustment of these parts has heretofore been made by bending and peening of the arms which is a far less accurate, permanent and generally satisfactory way of 120 doing it than that described as well as being far 125 more laborious and time-consuming and requiring a much higher degree of skill on the part of the workman.

What I claim as new and desire to secure by Letters Patent is:

1. In a computing machine, the combination with a rock shaft, a link, and an arm on said rock shaft and pivotally connected with said link, of means for adjusting said arm both as to its length and as to its position rotatively relative to said shaft and for securing said arm to said shaft in adjusted relation, said adjusting and securing means comprising a split sleeve on said shaft and having its exterior cylindrical surface eccentric to its bore, a split hub for said arm surrounding said sleeve, and a clamp screw for tightening said hub against said sleeve and thereby tightening said sleeve against said shaft.
2. Means for rigidly securing an arm to a shaft with provision for fine adjustment both of the

length of the arm and also of its position relative to the shaft, comprising a split sleeve surrounding the shaft and having its periphery eccentric to its bore, a split hub for the arm surrounding said

5 sleeve, and means for tightening said split hub about said sleeve and thereby tightening said sleeve about said shaft, whereby the length of the arm may be adjusted by turning said sleeve and the position of said arm may be adjusted by

10

a relative turning of said arm and shaft, and the whole assembly may be connected rigidly together in adjusted position by tightening said split hub about the sleeve and shaft.

3. The combination of a shaft, a split eccentric sleeve thereon, an arm having a split hub surrounding said sleeve, and the tightening means, as and for the purpose described. 80
